Attorney

UNITED STATES PATENT OFFICE.

FRANK D. MAXWELL, OF BOISE, IDAHO.

HAT.

Application filed August 11, 1925. Serial No. 49,553.

This invention relates to a hat construction and embodies an arrangement whereby same is suitable for wear during all seasons of the year and in addition is capable of 5 ventilation.

More specifically, the present invention includes a hat, the frame or body of which is shaped from wire mesh, preferably of non-corrosive character and is subsequently 10 covered by any suitable material to give the proper style or appearance. The covering is designed and secured in position in such a manner as to permit partial removal or adjustment from the screen body thereby 15 facilitating such ventilation as may be desired.

Other novel features of construction will more clearly hereinafter appear by reference to the following description and drawings, 20 wherein like numerals of reference designate corresponding parts throughout the several views, in which—

Figure 1 is a perspective view; and

Figure 2 is a vertical section.

Referring to the drawings, reference character 1 designates the frame or body which is formed from a suitable non-corrosive metallic mesh, such as brass screening, by stamping or shaping in a press or the like. 25 Obviously, while the present illustration represents one conventional type of present day hat, any suitable shape can be made to meet the demands of the market and the change in the styles. In the shaping of the 30 body, the crown 2 and rim 3 can be shaped as an integral structure or can be made separately and assembled in any suitable manner.

A covering 4 of any suitable material is 35 secured to the top surface of the rim and a similar covering 5 faces the bottom. An edging 6 binds the peripheral edge of the rim and encloses the adjacent edges of the rim coverings 4 and 5 to produce a finished 40 appearance.

The covering for the crown is made in the sections 7 and 8. The lower section 7 terminating at a point approximately intermediate the height of the crown and the 45 upper portion 8 terminating short of the

upper edge of the lower section a suitable distance to permit the insertion of the ventilating flap 10. This flap 10 is secured as by stitching to the portion 8 and its lower edge is free to permit folding upwardly, 55 either wholly or in part.

In the event ventilation is desired as in warm weather, the lower free edge of the flap 10 may be turned backward upon itself any extent desired, which will permit air 60 to gain access to the interior of the hat through the metallic mesh frame. The usual band 11 is shown to produce a finished article.

From the foregoing it will be seen that a 65 structure has been provided of a permanent character which, due to the elements of its construction, is capable of use in any season and which will not readily lose its shape and proper appearance. In addition by the 70 use of various covering materials and by changing the styles the demands throughout the various parts of the country, due to climatic conditions, can be more readily satisfied. Modifications in the details of 75 construction and arrangement of parts can be made without departing from the spirit of the invention.

What I claim as new and desire to secure by Letters Patent is:

A hat including a body formed of one piece of metallic screening shaped to provide a crown portion and a rim portion, a ring-like covering fitted over the rim portion and extending upwardly on the inside 85 and the outside of the crown to reinforce the fold in said body which defines between the crown and rim portions, a covering on the outside top portion of the crown and spaced at its edge from the first mentioned 90 covering, and a band joined at its upper edge to the crown covering in a manner to prevent bulging, the said band constituting a ventilating flap which extends to but is free from the outer edge of the ring-like 95 covering when in a closed position and is adapted to be upwardly folded to expose the body.

In testimony whereof I affix my signature.

FRANK D. MAXWELL.
